PASCAL P. CHILD, OF ST. LOUIS, MISSOURI, ASSIGNOR TO S. R. FOX
MANUFACTURING COMPANY, OF SAME PLACE.

Letters Patent No. 78,078, dated January 7, 1868.

IMPROVEMENT IN COMBINED LATCH AND BOLT.

The Schedule referred to in these Letters Patent and making part of the same.

TO ALL WHOM IT MAY CONCERN:

Be it known that I, PASCAL P. CHILD, of St. Louis, in the county of St. Louis, and State of Missouri, have made certain new and useful Improvements in Door-Lock Latches; and I do hereby declare that the following is a full and clear description thereof, reference being had to the accompanying drawings, and to the letters of reference marked thereon.

This invention relates to an improvement in that class of door-latches which are provided with a locking or stop-device, that prevents the latch being opened when required.

The improvement consists in a combination of a sliding-bolt latch with a peculiarly-constructed striker and keeper, by which means the latch can be used either as a latch or a bolt, as may be desired, as will hereinafter more fully appear.

To enable those skilled in the art to make and use my improved latch, I will proceed to describe its construction and operation.

Figure 1 is a front elevation of one of the improved latches as it would appear when in use.

Figure 2 is a plan of the same and a sectional plan of the door to which it is applied.

The face-plate A will be of any neat and approved plan, or contour of outline, and will be secured to the door B by means of the screws a a' , in much the usual manner. In the latches hitherto made, the guard-piece a^2 , which retains the latch in its relative lateral position, has been made in a separate, detached piece, and secured to the face-plate by means of the two screws a , which were passed through both it and the face-plate. In the present invention the construction of the latch and its application are both simplified and cheapened by having the said guard-piece a^2 cast as a part of the face-plate, as is shown in fig. 1. The back end of the face-plate is cast with a seat, into which the rear end of the latch enters, and where it is pivoted by means of the screw a' , which performs the double office of assembling the parts, and securing the latch to the door. Two segmental perforations, c c' , are made in the back end of the latch C, which perforations are connected by a slot, c^2 , of, say, half an inch in length, more or less. The width of the slot c^2 is just sufficient to allow the screw a' to be pressed through it, while the perforations c c' are of such a size as will allow the said screw a' to turn very easily therein. The diameter of the perforations should be, say, one thirty-second of an inch, (more or less,) larger than the width of the intervening slot. The keeper and striker D, which is secured to the jamb or casing of the door, for the engagement of the end of the latch when the door is closed, is constructed with a hasp-rail, d , (under which the latch slides when acting as a bolt or lock,) and two lug-plates, d' , by means of which it is secured to the jamb or casing by means of wood-screws in the usual manner. The front projections of the plates d' terminate in lugs d^2 , which are so disposed as to leave a notch, d^3 , between them, into which notch the end of the latch projects when used as a latch, as is clearly shown in fig. 1. The back sides of the adjacent ends of the said lugs are rebated, so as to form notches into which the latch drops when closed, and by this arrangement the door is securely latched. The outer side of the contiguous ends of the lugs d^2 are bevelled off so as to allow the latch to slide upon them when the door shuts. Both ends of the keeper and striker are made similar in this manner, so that the latch may be applied to a right or a left-hand door. The handle E and the thumb-piece F are made in the usual manner, and need not be minutely described. When this latch is to be used as a bolt or lock, the latch will be thrown forward under the hasp-rail d , as shown by red lines in fig. 1, the slot c c' c^2 permitting the required longitudinal motion of the latch.

Having described my invention, what I claim, is—

The sliding-bolt latch C, in combination with the keeper and striker D, the latter being constructed as described, with rebated projections d^2 , which act as strikers for the latch when it is used as such, and the hasp-rail d , which confines the latch when acting as a bolt, as shown and described.

PASCAL P. CHILD.
